ALBERT J. CHALLEEN, OF HIGHLAND PARK, MICHIGAN

SLEET CUTTER FOR TROLLEY WIRES

Application filed February 7, 1931. Serial No. 514,177.

The present invention pertains to a novel device for removing sleet and ice from a current conductor so that a bare surface of the latter is exposed for engagement by the current collecting member of an electric vehicle.

Certain devices of present construction are objectionable in that they do not provide sufficient outlet for the elimination of sleet removed from the trolley conductor, with the result that a layer of ice is eventually formed between the conductor and the cutter so that the metallic current path is interrupted and excessive arcing occurs. The arcing affects the normal current collector almost immediately since the latter is directly beneath the point where the arcing takes place. The formation of this layer of ice occurs principally because the bottom of the cutter rests directly upon the normal current collector or some other part, thus preventing elimination of loose sleet through the bottom of the device.

The objects of the present invention are to overcome these difficulties and are accomplished essentially by constructing the cutter in such a manner that the bottom thereof is disengaged from any other part and by providing ample elimination openings in the bottom. More specifically, the device may be conceived as consisting of two portions, one of which receives the normal current collector and the other of which projects horizontally therefrom and carries the cutting elements with the elimination openings. Another object of the invention is to provide a sleet cutter applicable equally to a trolley wheel or to a sliding shoe.

The invention is fully disclosed by way of example in the following description and in the accompanying drawings in which—

Figure 1 is a plan view of the novel cutter mounted upon a current collector;

Fig. 2 is a side elevation thereof, partly in section; and

Fig. 3 is a longitudinal section of the device.

Reference to these views will now be had by use of like characters which are employed to designate corresponding parts throughout.

In Figures 1 and 2 is illustrated a conventional forked harp 1 in which is rotatably mounted a conventional current collector 2. The stem 3 of the harp is bored as at 4 to be fitted on the upper end of a trolley pole and for another purpose which will presently appear.

The sleet cutter according to this invention is a generally curved conducting member 5 having at one end a shank 6 which slips into the bore 4. Directly adjacent the shank, the lower side of the member 5 is formed with a cavity 7 into which the collector 2 is adapted to fit as shown in Fig. 2. A portion of the wall of the cavity is arcuate as at 8 to engage either a part of a trolley wheel or one of the curved ends of a trolley shoe. Adjacent the arcuate wall portion 8 is a substantially straight wall portion 9 merging into the shank 6. When the collector is in the form of a shoe as in Fig. 2, the wall portion 9 engages one of the straight sides of the shoe, so that the shoe is firmly held in the cavity.

The part of the member 5 thus far described may be conceived as the portion which receives the current collector, and the cutter further includes another portion 10 extending substantially horizontally from the first mentioned portion and in the direction of travel. Owing to this relation, the portion 10 is entirely free from the part which receives the current collector, except where it unites therewith.

The upper surface of the portion 10 is preferably grooved as at 11 to engage the current conductor 12. Although the member 12 is here illustrated as a wire, it may be of any other shape, such as an overhead rail, and the upper surface of the portion 10 would be shaped accordingly to be guided along the

conductor. The base of the groove 11 is notched at intervals as at 13 to form spaced cutting edges 14 lying transversely of the groove and the conductor 12 and thus adapted to 5 scrape the lower surface of the latter. Passages 15 are formed from the spaces between the cutting edges 14 through the bottom of the extended portion 10 to provide an escape for the sleet or ice released by the edges 14. It may here be pointed out that this means of escape is considered to be a distinct improvement over devices hitherto proposed, inasmuch as the latter afford no elimination through the bottom but rather have 10 a solid bottom which contributes to the formation of a layer of ice between the bottom of the conductor 12 and the subjacent metal part. In addition to the passages 15, lateral ports 16 are formed transversely through the portion 10 to communicate with the passages 15 or with the spaces between the cutting edges 14.

A downwardly extending hook 17 is formed as an integral part of the member 5, preferably at the side of the cavity 7 opposite the straight wall 9. After the device has been mounted on the current collector, the usual trolley rope 18 which is attached to the harp is thrown over the hook as shown in Fig. 2 in order to maintain the cutter more firmly on the collector.

In the event that arcing should occur between the conductor 12 and the portion 10, the portion of the rope thrown over the hook 17 is shielded by a flap of insulating material 19 pivotally attached to the member 5 and covering the hook. Inasmuch as the portion 10 is considerably offset from the collector 2, the arcing will not damage the collector. If 25 the arcing is sufficient to burn off the portion 10, the remainder of the portion 5 is still serviceable as an emergency collector and cutter in that it is formed in its top with a continuation 11' of the groove 11 and also with 30 cutting edges 14' which are below the normal cutters 14.

Although a specific embodiment of the invention has been illustrated and described, it will be apparent that various alterations in 35 the details of construction may be made without departing from the scope of the invention as indicated by the appended claims.

What I claim is:—

1. A sleet cutter having a portion adapted 40 to fit upon a current collector and another portion projecting substantially horizontally from the first portion to be offset from a collector fitted into the first portion, the second portion being adapted to ride along a current conductor, cutting devices across the top of said second portion and spaced lengthwise thereof, and outlet means extending from the spaces between said cutting devices to the outer surface of said second portion.

2. A sleet cutter having a portion adapted

to fit upon a current collector and another portion projecting substantially horizontally from the first portion to be offset from a collector fitted into the first portion, the second portion being adapted to ride along a current conductor, cutting devices across the top of said second portion and spaced lengthwise thereof, said second portion having outlet passages from the spaces between said cutting devices to the bottom outer surface of said portion. 70

3. A sleet cutter having a portion adapted to fit upon a current collector and another portion projecting substantially horizontally from the first portion to be offset from a collector fitted into the first portion, the second portion being adapted to ride along a current conductor, cutting devices across the top of said second portion and spaced lengthwise thereof, said second portion having outlet 80 passages from the spaces between said cutting devices to the lateral surfaces of said portion. 85

4. A sleet cutter having a portion adapted to fit upon a current collector and another portion projecting substantially horizontally from the first portion to be offset from a collector fitted into the first portion, the second portion being adapted to ride along a current conductor, cutting devices across the top of said second portion and spaced lengthwise thereof, said second portion having outlet 90 passages from the spaces between said cutting devices to the bottom outer surface and the lateral surface of said portion. 95

5. A sleet cutter having a portion adapted to fit upon a current collector and another portion projecting substantially horizontally from the first portion to be offset from a collector fitted into the first portion, the second portion being adapted to ride along a current conductor, cutting devices across the top of said second portion and spaced lengthwise thereof, outlet means extending from the spaces between said cutting devices to the outer surface of said second portion, a hook 100 extending from one of said portions and adapted to engage the trailing end of a collector received in the first portion, and a flap attached to one of said portions and adapted to cover said hook. 105

6. A sleet cutter having a portion adapted to fit upon a current collector and another portion projecting substantially horizontally from the first portion to be offset from a collector fitted into the first portion, the second portion having a groove adapted to receive a current conductor, cutting devices across said groove and spaced lengthwise thereof, and outlet means extending from the spaces between said cutting devices to the outer surface of said second portion. 110

7. A sleet cutter having a portion adapted to fit upon a current collector and another portion projecting substantially horizontally from the first portion to be offset from a col- 115 120 125 130

lector fitted into the first portion, the second portion being adapted to ride along a current conductor, cutting devices across the top of said second portion and spaced lengthwise 5 thereof, and outlet means extending from the spaces between said cutting devices to the outer surface of said second portion, the first portion being also adapted to ride along a current collector and having transverse cutting 10 devices below the normal operative plane of the first named cutting device.

In testimony whereof I affix my signature.
ALBERT J. CHALLEEN.
